LOCKED JOINT FOR METAL STRUCTURES

Henry W. Toney, Niles, Mich., assignor, by mesne assignments, to Kawneer Company, a corporation of Delaware

Application August 31, 1949, Serial No. 113,317

5 Claims. (Cl. 189—36)

This invention relates to metal structural assemblies, particularly a novel form of locked joint for metal structures. The invention is of general application, but is particularly well suited to construction of prefabricated metal units such as flush doors, and will accordingly be described in connection with such a structure.

It is the primary object of the invention to provide an improved and simplified locking joint whereby the several individual parts of a metal assembly may be rigidly and permanently secured to each other by means that are inexpensive, yet so designed that various sizes of parts may be easily manufactured with unusual uniformity as to dimensional variations, so that they may easily meet the most strict requirements as to manufacturing tolerances.

A further object of the invention is to provide a novel and improved locking joint for metal structures wherein the commonly employed mechanical expedients of welding, drilling, tapping and riveting are eliminated, so that the product produced is rigid and structurally strong, yet its appearance is not marred by the presence of rivets, screws or welding seams.

A still further object of the invention is to provide a prefabricated panel suitable for structural uses such as flush doors, etc., formed of thin face sheets with relatively heavy reinforcing rails around their edges, with the sheets and rails united by joints according to the foregoing.

One of the most obvious uses for the present invention is for the construction of prefabricated metal doors as disclosed in the drawings of the present specification, wherein:

Figure 1 is a front elevational view of a prefabricated metal door constructed in accordance with these teachings;

Figure 2 is a fragmental detail elevational view of one corner of the door structure;

Figure 3 is a fragmental detail sectional view taken on the plane of the line 3—3 of Figure 1;

Figure 4 is a detail sectional view similar to Figure 3 showing the shape of the parts before they are locked together; and

Figure 5 is an enlarged fragmental sectional view of the locked joint between the face sheets and rails which form the door.

The novelty of the invention resides in the locked joint illustrated in Figure 5, and while this joint is of general application for various structural uses, it is particularly well suited to the construction of prefabricated flush metal doors as illustrated in Figure 1. As illustrated, the door frame comprises vertical rails 10 and 11 with top and bottom rails 12 and 13, provided with front and back panel sheets 14. The entire marginal edges of each of the front and back sheets are locked to the rails by the novel joint here disclosed.

The rails 10, 11, 12 and 13 comprise relatively heavy metal shapes, preferably being aluminum or alloy metal extrusions of generally channel shape having a body por-

2

tion 15 extending between two side flanges or webs 16. The channels shown have flat end faces 17 around the entire door, and the inside corners of the channels have thickened portions 18 in which a pair of relatively deep, narrow grooves 19 are formed, each groove being defined by permanently oriented spaced substantially parallel walls formed by body member 15. These grooves lie on the opposite sides or edges of the rail and are spaced slightly back from the lower flat end surfaces 17. The sheet metal panel sheets 14 have short, right-angled flanges 21 along all of the four marginal edges of the sheets, the flanges 21 being preferably formed by bending so as to provide curved outer marginal surfaces 22 on each sheet adjacent the flanges 21. The webs 16 of the rails include flat inside supporting or abutment faces or surfaces 23, which lie against the inner faces 24 of the sheets 14. Narrow front and back edge face surfaces 25 are formed at the opposite edges of the end faces 16 of all of the rails. These edge face surfaces 20 are located in the same plane as the exterior face surfaces 26 of the front and back sheets 14. The faces 23 may be referred to as recessed with respect to faces 25.

A deformable locking lip or bead 27 is provided along the outer edge of each of the grooves 19. This lip, before the parts are assembled, constitutes a tapered or pointed ridge, between the groove and the edge face surface 25 of the rail, and extending along the entire length of the groove, with an exposed face surface 28 lying at an angle to the plane of the panel. The structure is assembled by cutting the several parts to shape, inserting the flanges of the plates 14 into the grooves 19 of the rails around the entire marginal edge of the panel, and passing the entire assembly between pressure rollers to press the locking lips 27 flat as illustrated in Figures 3 and 5. As shown in Figs. 3, 4 and 5, the grooves 19 are dimensioned to approximately the same thickness as the flanges 21, thereby providing a relatively close fit therebetween, so that the flanges may be readily positioned in the grooves for the rolling operation. As a result of the pressure rolling, the lip 27 is bent inwardly so that its outer exposed face surface 28 lies flush with the outer face surface 25 of the rails, and flush with the exterior surfaces 26 of the panel sheets 14. The locking lips 27 thus overhang the grooves 19 in which the flanges 21 of the sheets 14 are seated, and bear against the curved surfaces 22 of the panel sheets to lock the flanges 21 in the grooves. This forms a permanent, interlocking joint between panel sheets and the top, bottom and side rails of the structure.

It is to be noted that the completed door is free of any welding seams or conventional fastenings such as rivets, screws and other conventional devices, yet the entire assembly is rigidly assembled in such a manner that the individual parts cannot become accidentally released. The exterior of the door panel is flush, with all exposed surfaces lying in a substantially continuous, unbroken plane. The exterior surface may be provided with ornamentation as indicated at 29 (Figure 2), but this is not essential to the practice of the invention and may be omitted if desired. The metal sheets forming the front and back faces of the panel may be rolled with a slight tension if desired, so that the assembled unit will form a girder with no back stiffeners, and thus give maximum strength for the weight of metals involved.

It will be clear to those skilled in the art that the structure as here disclosed is comparatively inexpensive to manufacture, since it avoids all drilling, tapping, riveting, welding and other conventional expedients for joining the several parts, yet is well adapted to production in all sizes and shapes, and may be produced in factory production methods with dimensional stability within

much closer tolerances than can be obtained by operations such as welding. Thus, while the invention is particularly useful in connection with the manufacture of flush metal doors as here disclosed, it is of broader application, and may be employed wherever it is advantageous to unite a grooved section with the flanged edge of a relatively thin sheet to form an integral structure with a permanently locked joint.

Having thus described my invention, what I claim as new and desire to secure by United States Letters Patent is:

1. A panel assembly comprising in combination: a pair of substantially flat panel members each having an edge flange; and a preformed rail member; said rail member comprising an elongated body member having a pair of opposed grooves extending longitudinally thereof, each groove being defined by permanently oriented spaced substantially parallel walls formed by said body member, with a first face of said body member extending transversely to said groove along one lip thereof, and with a second face of said body member extending transversely to said groove adjacent the other lip thereof, and a deformable bead projecting outwardly from each said second face at the second mentioned lip of each groove, said panel flanges closely fitting, one in each of said grooves, with the portion of each panel extending from the respective groove directed away from the respective bead; whereby said panels may be locked into permanent structural assembly with said rail by deformation of said beads into overlapping relation with the respective panels in the region of the respective flanges.

2. A panel assembly comprising in combination: a substantially flat panel member having an edge flange; and a preformed rail member; said rail member comprising an elongated body member having a groove extending longitudinally thereof, said groove being defined by permanently oriented spaced substantially parallel walls formed by said body member, a first face of said body member extending transversely to said groove along one lip thereof, a second face of said body member extending transversely to said groove adjacent the other lip thereof, and a deformable bead projecting outwardly from said second face at the second mentioned lip of said groove, said panel flange closely fitting in said groove with the portion of the panel extending from the groove directed away from the bead; whereby said panel may be locked into permanent structural assembly with said rail by deformation of said bead into overlapping relation with the panel in the region of the flange.

3. A structural assembly comprising, in combination, a relatively thin flat sheet having a flange extending a short distance from an edge; and a preformed elongated metal rail having an end portion extending generally in the direction of said flange on the sheet and a sheet supporting portion extending in the direction of said sheet, said rail having a groove adjacent said sheet supporting portion substantially coextensive in length with said flange, in which said flange is positioned, and which is dimensioned closely to receive said flange, said groove being formed by rigid permanently oriented walls in said rail, the portion of the rail beyond said groove and the sheet supporting portion each having a substantially flat surface, said sheet supporting portion being recessed with respect to the portion of the rail beyond said groove by a distance corresponding substantially to the thickness of said sheet, said portion of said rail beyond said groove having a small deformable bead preformed with the rail and extending outwardly from the rail substantially parallel with said groove and adjacent thereto, whereby said bead may be deformed to extend over a portion of the outer surface of said sheet in the region of said flange

4
for locking the rail and sheet in permanent assembled relation.

4. A structural assembly comprising, in combination, a pair of opposed, parallel, relatively thin flat sheets each having a marginal flange extending from a side towards the marginal flange of the other sheet; and a preformed metal rail including spaced, parallel edges each receiving an edge of one of said sheets and each having a length substantially coextensive with the edge of the sheet received, said rail also including an end portion interconnecting said rail edges and extending generally parallel to the flanges on said sheets, said rail edges each including a sheet supporting portion extending generally in the direction of the received sheet, and also including a groove substantially coextensive in length with the flange on the sheet associated therewith, each of the grooves being formed by flat, parallel, permanently oriented walls spaced apart substantially the thickness of its associated sheet and engaging the opposite sides of the flange thereof, the portion of each edge of the rail beyond the groove therein and the sheet supporting portion on each edge both having a substantially flat surface, the sheet supporting portion of each rail edge being displaced in the direction of the groove from the portion of the rail edge beyond said groove by a distance corresponding to the thickness of the sheet supported thereon, and small deformable beads preformed with the rail at positions adjacent each of the grooves in said rail edges, whereby each of said beads may be deformed to extend over a portion of the outer surface of each sheet in the region of its flange in order to lock the rail and the sheets in assembled relation.

5. A preformed metal rail for use in structural assemblies comprising a relatively long body member having first and second edges and an end portion interconnecting said edges, each of said edges having a groove formed therein intermediate its marginal ends, the groove in each of said edges being formed by opposed, rigid, flat, parallel walls spaced apart a predetermined distance, small, deformable beads formed integral with said body member, one on each of said edges adjacent a first flat wall of the groove therein, each of said deformable beads extending outwardly from the edge on which it is formed in a direction generally parallel with the flat walls of the adjacent groove, each of said edges having a first flat face portion extending from the bead formed thereon to the end portion interconnecting said edges, and also having a second flat face portion extending from the second wall of said groove away from said first flat face portion, said second flat face portion extending parallel to the first flat face portion but being displaced therefrom in the direction of the other edge of the body member, whereby the first wall of each of said grooves is longer than the second wall thereof.
